UNITED STATES PATENT OFFICE

ERNEST R. ERICKSON, OF DES MOINES, IOWA, ASSIGNOR TO C. E. ERICKSON COMPANY, INC., OF DES MOINES, IOWA

OILMETER

Application filed April 29, 1930. Serial No. 448,233.

The object of my invention is to provide an oilmeter or device for indicating the mileage at which a motor vehicle should be greased or oiled.

- 5 More particularly is it my object to provide an oilmeter of very simple and inexpensive construction which can be conveniently and easily mounted in a motor vehicle and adjusted for indicating mileage.
- 10 With these and other objects in view my invention consists in the construction, arrangement and combination of the various parts of my device, whereby the objects contemplated are attained, as hereinafter more 15 fully set forth, pointed out in my claims, and illustrated in the accompanying drawings, in which:

Figure 1 shows a perspective view of a portion of the interior of a motor vehicle having one of my oilmeters installed thereon.

Figure 2 is a front elevation of the oilmeter.

Figure 3 is a side elevation of the same.

Figure 4 is a vertical sectional view taken 25 on the line 4—4 of Figure 2.

Figure 5 is a detail sectional view of the oilmeter taken on the line 5—5 of Figure 4.

Figure 6 is a perspective view of one of the movable dial members or bands; and

30 Figure 7 shows a plan of the blank from which my device is formed.

It is well known that it is the custom of those who service automobiles to place stickers on the car and to mark on the sticker the 35 mileage at which the car will require further attention, as for instance, in the matter of cylinder oil.

It is my purpose to provide a small, simple and inexpensive novel mechanical device 40 which can be easily and readily mounted in the car and adjusted from time to time to indicate the proper mileage. My device is of the kind which can be sold as an advertising novelty and given as a premium, or sold as a 45 standard commercial article.

Generally speaking, my device consists of a cylinder having a series of sight openings arranged in a row and having rotatable bands or dial members on its inside provided 50 with indicating characters and so arranged

that different indicating characters may be brought to the sight openings.

In Figure 7 I have shown the blank from which my oilmeter is formed. It is preferably made of sheet metal which can be readily bent and the blank has a substantially rectangular portion indicated in the drawings by the reference numeral 10 which forms the back or supporting member. Extending from the plate 10 is a substantially rectangular portion 12 intended ultimately to be rolled into a cylinder 14 such as is shown in Figure 2. The plate 10 has secured thereto disk shaped members 16 adapted to ultimately form the ends of the cylinder. The portion 12 of the blank and the end members 16 are provided with short tongues 17 and 18. The portion 12 like the portion 10 is provided with spaced slots 19 and the portion 12 at its opposite end is provided with tongues 20.

In fabricating the meter the portion 12 of the blank is rolled to form a cylinder 14 as shown in Figures 2 and 3 and the tongues 20 are extended through the slots 19. The tongues 20 are provided with holes 22. After 75 the tongues 20 have been inserted through the slots 19, pin members 24 are inserted through the holes 22, as shown, for instance in Figures 3 and 5 for holding the cylinder 14 in assembled position.

The lower ends of the pin members 24 are inclined slightly away from the plate 10 as indicated at 24a, of Figure 3. The upper ends of the pins 24 are connected by a substantially V-shaped portion 26. It will be 85 understood that the pin members 24 and the V-shaped portion 26 are of somewhat resilient stiff wire. The blank portion 12 has a tongue 28 projecting from it as indicated in Figure 3. The parts are so arranged that the upper part of the V-shaped portion 26 of the locking structure stands just below the tongue 28 as shown in Figure 3 and by dotted lines in Figure 2.

The blank has in the portion 12 a row of 95 sight openings 30. Before the end members 16 are closed I insert into the cylinder 14 a row of dial bands 32. These are in the form of broken rings as shown and have on their outer surfaces indicating characters 34, pref. 100

erably running from 0 to 9, and regularly spaced. Their indicating characters are of such size with relation to the sight openings 30 so that one character may be made readily visible through a sight opening. It will be understood that the sight openings are so spaced and are of such size, and that the bands 32 are of such size and width, that the bands 32 fit snugly in the cylinder 14 in a row and are rotatable. After the bands 32 are placed in the cylinder, the ends 16 are closed and the tongues 17 are bent over so that the ends will be snugly held in place. The tongues 18 in conjunction with the notches 18a, serve to align the parts.

In the right hand corner of each of the openings 30 as they appear in Figure 2, the material of the cylinder 14 is cut away slightly so as to afford openings 36 to receive a pin 38 on the right in such manner that half of the pin 38 will project into the side opening 30. The bands 32 are provided on one edge with a series of holes 40 properly spaced and located so that a pin may be inserted through the hole 36 to a hole 40 and when the pin is moved across the sight opening 30 the band will have been moved for bringing another indicating character into the sight opening.

I shall now describe the practical use of my oilmeter and refer to some of its objects.

It will be seen from the foregoing that a single piece of metal is used to form the plate 10, the cylinder 14 and the ends 16. The yoke shaped pin structure is used in fastening the piece in assembled position. The bands 32 are of the simplest construction, being plain broken rings as shown. The pin members 24 may be inserted into the fabric 42 lining 42 of a car as shown in Figures 1 and 4 and an account of the arrangement of the plate 10 the metal will then be held in position. The tongue 28 prevents the accidental removal of the pin structure.

After the car has been greased and oiled the dial operating pin 38 may be inserted through the holes 36 and sight openings 30 into the holes 40, for rotating the bands 32 and bringing to the sight openings the proper characters 34 for indicating mileage at which the car should again be serviced. The pin can be stuck into the fabric 42 forming the lining of the car 44 somewhere close to the oilmeter so that it will always be readily available.

Some changes may be made in the details of the structural arrangement of my improved oilmeter without departing from the essential purposes of my invention and it is my intention to cover by my claims any modification in the arrangement of structural parts which may reasonably come within the scope of my invention.

I claim:

1. In a device of the class described, a plate,

a cylinder at one end thereof formed by rolling a portion of the material of the plate into shape, said plate having slots and said portion having tongues projected through said slots and provided with openings and pin members extended through said openings for holding the cylinder in assembled position.

2. In a device of the class described, a plate, a cylinder at one end thereof formed by rolling a portion of the material of the plate into shape, said plate having slots and said portion having tongues projected through said slots and provided with openings and pin members extended through said openings for holding the cylinder in assembled position, said cylinder having means for preventing the accidental removal of said pin members.

3. In a device of the class described, a plate, a cylinder at one end thereof formed by rolling a portion of the material of the plate into shape, said plate having slots and said portion having tongues projected through said slots and provided with openings and pin members extended through said openings for holding the cylinder in assembled position, said pin members being connected at their upper ends by a substantially V-shaped wire element and means on said cylinder for engaging the apex of said element for holding the pin members against accidental removal.

4. In a device of the class described, a plate, a cylinder at one end thereof formed by rolling a portion of the material of the plate into shape, said plate having slots and said portion having tongues projected through said slots and provided with openings and pin members extended through said openings for holding the cylinder in assembled position, a series of bands rotatably received end to end in said cylinder having rotating characters arranged on their surfaces and having holes, said cylinder having sight openings for the respective bands.

5. In a device of the class described, a plate, a cylinder at one end thereof formed by rolling a portion of the material of the plate into shape, said plate having slots and said portion having tongues projected through said slots and provided with openings and pin members extended through said openings for holding the cylinder in assembled position, a series of bands rotatably received end to end in said cylinder having rotating characters arranged on their surfaces and having holes, said cylinder having sight openings for the respective bands, and an operating pin adapted to be inserted through the sight openings and into said holes for rotating said bands for bringing different characters into position where they are visible through the slot.

6. In a device of the class described, a plate, a cylinder at one end thereof formed by rolling a portion of the material of the plate into shape, said plate having slots and said por-

tion having tongues projected through said slots and provided with openings and pin members extended through said openings for holding the cylinder in assembled position,
5 said pin members being connected at their upper ends by a substantially V-shaped wire element and means on said cylinder for engaging the apex of said element for holding the pin members against accidental removal,
10 a series of bands received in said cylinder having indicating characters on their surfaces, said cylinder having a series of sight openings and end members for closing the ends of said cylinder.

15 Des Moines, Iowa, April 14, 1930.
ERNEST R. ERICKSON.
